REFRACTORY LINED RECEPTACLE

Nels E. Werner, Detroit, Mich., assignor to Bigelow-Liptak Corporation, Detroit, Mich., a corporation of Michigan

Application January 13, 1945, Serial No. 572,695

5 Claims. (Cl. 72—14)

1 In large, lined, cylindrical metal tanks or vessels with conical bottoms and tops and equipped with appropriate admission and discharge conduits employed, for example, as set forth in my copending patent application Serial No. 470,992, Lined Containers, filed January 1, 1943, now Patent No. 2,460,052, dated January 25, 1949, in the regeneration or restoration of catalysts in powdered or finely divided form used, for instance, in the production of high-octane fuel for internal-combustion engines, the heat, pressure, abrasive effects and gas flows prevailing in such container render the protection of the metal enclosure or receptacle against the development of dangerous hot-spots in the metal wall a problem or difficulty the solution of which has caused much trouble and anxiety.

Such catalyst is an efficient abradant and its coating of carbon deposited thereon during the performance of its catalytic function is burned off and thus disposed of in such tank, the temperature therein reaching approximately 1000° F.—1200° F. and the gas or fluid pressure in such vessel is about 5 pounds per square-inch, such gas charged with the catalyst to be treated also having a swirling action, and the protective lining of such a container, which is frequently of 45 ft. in diameter and 90 ft. high, must under all varying conditions effectively shield and protect the metal-shell.

Obviously, the internal temperature is high and the gases at such temperature and their contained abradant are in direct contact with the refractory-tile lining, and the heat of such tiles must be prevented from reaching the metal shell in substantial or destructive measure, this being accomplished by suitable insulation completely filling the volumetric space, not otherwise occupied, between such refractory-lining and the wall.

The pressure varies greatly and suddenly tending to set up serious vibrations and dislodgements of the tiles, especially those lining the lower, inverted-cone bottom-wall of the vessel, and, accordingly, the novel and improved means embodying the present invention have been employed to solve such problem.

The indicated 5 pound pressure may abruptly and substantially-instantaneously change to two pounds or three pounds per square-inch, but this quick variation while instantly applicable to the inner or upper surfaces of such tiles lining the bottom cone does not have corresponding immediate access to the under or outer surfaces of these tiles, so that, since the area of the back or under surface of such a tile is approximately

5 fifty square-inches, the instantaneous force on an individual tile with a 3 pound differential would result in a pressure of one hundred and fifty pounds tending to dislodge the tile, and, in like manner, if the differential were 5 pounds per square-inch that same displacing and unseating force would reach a magnitude of approximately two hundred and fifty pounds.

In addition, owing to the swirling or circumrotatory action of the catalyst-charged, gaseous contents of the tank, there is a distinct tendency to dislodge the tiles additionally, horizontally, circularly on their supports and the current invention provides means to preclude the occurrence of any detrimental action or effects from such a cause.

20 Stated succinctly one of the main objects of the present invention is to provide means for lining the side walls and the bottoms of such containers and the walls of associated pipes or conduits in a manner to give satisfactory and prolonged service regardless of the occurrence of the conditions stated above.

To enable those skilled in this art to understand the invention from both structural and functional standpoints, present preferred embodiments thereof have been illustrated in the accompanying drawings forming a part of this specification and to which reference should be had in connection with the following detailed description, and for simplicity like reference numerals have been employed in the several views of the drawing to designate the same parts.

25 In these drawings:

30 Figure 1 is a fragmentary vertical section through the bottom, inverted-cone portion of the lined container or tank;

35 Figure 2 is a partial horizontal section of the same construction on line 2—2 of Figure 1 and with the insulation-lining omitted to more clearly depict the other structural elements;

40 Figure 3 presents an enlarged portion of Figure 1;

45 Figure 4 is a section on line 4—4 of Figure 1;

50 Figure 5 is a cross-section of a pipe or conduit embodying the current invention; and

Figure 6 is a fragmentary section on an enlarged scale taken through the wall of, and lengthwise the axis of, the conduit illustrated in Figure 5.

55 Referring first to Figures 1 to 4 inclusive, it will be noted that the conical metal-wall of the sloping bottom of the container is designated as 11 and at intervals along it and at different levels circular rows of metal-supports 12 are

welded to its inner or upper surface and to the opposite flanges of each such member 12 the longitudinally-slotted ends 13 of curved bar-sections 15 are bolted at 14, such aligned bars of any one annular set constituting in effect a single, circular, sectional bar, and it will be considered as such herein, with the slot expansion and contraction compensating-means at each such support 12, these ring bars 15 being concentric with wall 11 and with their bodies disposed vertically, as clearly shown in Figures 1 and 3.

Supported by and slidably mounted on each such circular-bar 15 is a number of spaced-apart brackets or clips 16 located around the entire circle, each such bracket having an outwardly extended arm 17 resting and bearing on the top edge of its bar 15, such arm having a downwardly-extended, terminal projection 18 (Fig. 3) overlapping, and normally contacting with, the upper portion of the back or outer face of the bar.

Each such bracket also has a lower arm 19 beneath the bar and equipped with an upwardly-extended projection 21 overlapping the lower part of the same surface of the bar.

On the opposite side of the bar 15 the bracket or clip has upper and lower lugs 22 and 23, respectively, as portrayed in Figure 3, lug 23 ordinarily engaging the inner or front face of bar 15.

Each such bracket has an inclined web terminating in a double-flange or plate-portion 24 substantially parallel to the metal-wall 11, the two oppositely-extended parts of which occupying mating grooves 25 across the top of one tapered refractory-tile 26 and 27 in the bottom of the corresponding refractory-tile 28 of the next row, the grooves 25 of all of the tiles in that circular row forming a single, continuous or endless groove, the same being true of the aligned grooves 27 of that row of tiles.

It will, of course, be understood that the portions 24 of these several brackets hold their corresponding tiles in place.

In addition, each tile 26 across its top has a tapered rib 29 occupying a correspondingly-shaped groove 31 in the bottom of the next upper tile 28.

Between the tile-lining and the metal-wall the entire otherwise-unoccupied space is filled with insulation 30, some in the form of blocks or insulating-bricks, or parts thereto fashioned to fit around the intervening metal members and some in the form of insulating-cement 32, which among other spaces occupies those in and around the brackets.

These brackets support and position the tiles by their arms 17 resting on the tops of their companion bars 15, by the engagement of the projections 18 with the rear faces of the bars 15, and by the contact of the lower lugs 23 with the front faces of the bars 15.

When a sudden, substantial reduction in the internal pressure in the tank occurs there is an instantaneous tendency for the tiles to move upwardly by reason of the temporary continuance of the greater pressure on their undersides, but this influence is overcome by the pressure of the projections 21 against the rear faces of the bars 15 through the thin, intervening films of insulating-cement and the pressure of the lugs 22 against the front surfaces of the bars 15 through the intermediate scant layers of the insulating-cement.

Inasmuch as the mounting of these brackets

16 on their bars 15 involves the sliding along of the brackets on such bars to properly position them in spaced-apart relation, all four parts 18, 21, 22 and 23 could not well be made to fit tightly against both faces of the bars and for that reason the very shallow gaps are employed between the parts 21 and 22 and the bars 15, but these spaces are filled with cement so that the brackets can perform their functions as stated above.

In order to prevent the tiles of any horizontal row from moving around circularly on their brackets and to debar the brackets from becoming improperly spaced apart or in other words, 15 to center the brackets on the respective tiles spacers 33 are employed in the matching grooves 25 and 27 between and in cooperative spacing relation with the parts 24 of the brackets, although in some instances the spacers may be of such size 20 as to occupy only the one 25 of the two continuous grooves or channels.

It is also desirable or essential to prevent the brackets themselves from traveling around circularly on their supporting bars 15 and at spaced intervals, say about every 5 ft., projections of 25 welding metal are welded to the top edge of the bars 15 on opposite sides of the bracket at that point, such projections being characterized 34.

From the foregoing it will be observed that 30 none of the parts of the refractory-tile lining and its supporting means can travel around or be displaced circularly by whatever whirling movement may occur in the interior of the tank.

As is presented in Figure 2, some of the offset, 35 lengthwise joints between the refractory-tiles in the same circular row are closed by sealing insulating-cement 35, whereas the other like joints or spaces 36 are left open to permit expansion of 40 the tiles as they become heated.

In practice, every alternate or third joint is ordinarily left open for this purpose.

It is to be noted that the loose fit of the bracket-heads 24 in the tile-grooves allow the tiles to be 45 held pressed outwardly against the insulation-lining by reason of the pressure inside the tank when the latter is in operation, whereby to force the insulation-lining against the inner face of the metal vessel to preclude the development of lan- 50 ging currents of the abradant-charged gasses in the tank.

If such access of the contents of the tank to the 55 metal-wall is permitted in the most minor degree, the abrasive property of the material will bore its way through and enlarge any tiny passage available so that the high heat will reach the metal of the tank with danger of rendering the tank unserviceable, a matter of great importance be- 60 cause of the interruption of the expected service and because it renders the high cost of the equipment a serious non-productive factor.

The gas-borne catalyst enters the tank at the 65 bottom of the lower, cone-shaped wall of the container and for that reason the present invention is particularly valuable in the mounting of the tiles and insulation on the inner surface of such portion of the apparatus.

Turning now to the novel pipe or conduit construction illustrated in Figures 5 and 6, this is 70 much like that described above except that such conduct is cylindrical instead of conical and the structural features necessarily conform to such difference, the various corresponding elements 75 or structural members being supplied with com-

parable reference numerals heretofore employed but supplemented by 100.

In this case, as indicated in Figure 5, the refractory bricks or tiles of any annular row are fitted tight together without any expansion joints between them and such tiles are not longitudinally tapered because the pipe is of uniform diameter throughout.

The object of the absence of such expansion-joints is to utilize the circumferential enlargement of such rows under heat to create a greater pressure of the refractory-tiles against the insulation-lining to force the latter outwardly into firmer contact with the interior surface of the metal-shell to bar or exclude the fluid or gaseous contents of the tank from having access thereto, which, if permitted to occur, would probably result in serious damage.

This conduit construction also uses the spacers 133 between the brackets or clips 116 and the elevations or projections 134 on the supporting-bars 115 on opposite sides of the parts 116, such elements 134, in this case, being indicated and shown as employed with each bracket, but, in some cases it is feasible and desirable to employ them with a lesser number of the brackets.

Those acquainted with this art will readily understand that this invention as defined herein-after is not necessarily limited and restricted to the precise details of structure set forth, and that reasonable modifications may be resorted to without departure from the heart and essence of the invention and without the loss or sacrifice of its substantial benefits and advantages.

I claim:

1. In a container or the like having an outer wall, the combination of a horizontal support member within the container, a horizontal row of refractory blocks having vertical joints between the vertical side faces of adjacent blocks, said blocks having recesses opening into said vertical faces and extending from face to face across each block, mounting brackets in said recesses and disposed intermediate the vertical side faces of the blocks, said brackets being mounted on said support member to suspend the blocks thereon, and spacers in said recesses extending across said joints to unite adjacent blocks and to space said brackets.

2. The invention as set forth in claim 1 wherein the recesses in adjacent blocks register with each other to form a continuous groove extending horizontally across the row.
3. The invention as set forth in claim 1 wherein at least some of said brackets are movable on the support member.
4. In a container or the like having an outer wall, the combination of vertically spaced horizontal support members within the container, horizontal rows of refractory blocks, the top and bottom faces of said blocks having horizontally extending grooves therein opening also into opposite vertical sides of the blocks, the grooves in the blocks of one row registering with the grooves in the blocks of the adjacent row, common brackets for vertically adjacent blocks having upwardly and downwardly extending flanges in the registered grooves and located intermediate the opposite vertical sides of the block, common spacers for vertically adjacent blocks in said grooves and extending across the joints between the vertical sides of horizontally adjacent blocks to unite horizontally adjacent blocks and to space said brackets, said brackets being mounted on said support members.

5. The invention as set forth in claim 4 wherein in the grooves in all horizontally adjacent blocks register with each other to form continuous grooves extending across the rows and wherein said spacers and brackets are slidably in said grooves and at least some of said brackets are movable on said members.

NELS E. WERNER.
